(57) **CLAIM**

The ornamental design for electric massager, substantially as shown and described.

DESCRIPTION

FIG. 1 is a front perspective view of an electric massager showing our new design;

FIG. 2 is a perspective view thereof as seen from behind;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side view thereof;

FIG. 8 is a left side view thereof; and,

FIG. 9 is a right side view thereof shown in a rearward inclined alternate position.

The massager comprises a pair of recessed portions for inserting the user's legs (portions including mainly from calves to feet) to be massaged. The recessed portions are rockingly movable forward and rearward relative to a base assembly placed on the floor.
